UNITED STATES PATENT OFFICE

JETZE VAN HOORN, OF VOORBURG, NETHERLANDS, ASSIGNOR TO U. S. SLICING MACHINE COMPANY, OF LA PORTE, INDIANA, A CORPORATION OF INDIANA

MOTOR-DRIVEN SLICING MACHINE

Application filed April 27, 1928, Serial No. 273,172, and in Great Britain May 4, 1927.

This invention relates to motor-driven slicing machines of the kind in which the substance to be sliced is carried past a rotary knife, toward which the substance can be fed either automatically in the working of the machine or by hand.

In slicing certain substances, it is desirable to be able to slow down the rate of slicing (that is, the speed of the substance past the knife).

With the motor-driven machines used at present, such slowing down would be accompanied by proportionate slowing down of the rotational speed of the knife, this being disadvantageous.

The present invention comprises a slicing machine of the kind referred to in which the knife is rotated by an electric or other motor while the carriage for the substance to be sliced is also operated by the motor but through the intermediary of a slip-coupling, the arrangement being such that the speed of the carriage and, consequently, the rate of slicing, can be varied by the operator to suit the substance being sliced, the speed of the knife remaining constant.

Preferably, the parts are so arranged that, by pushing or pulling the carriage by hand while it is being reciprocated by the motor, the driving force applied thereto through the slip-coupling can be added to or diminished in order to vary the speed of the carriage, so that the operator may vary the rate of slicing as desired, this being particularly useful when slicing substances containing layers of soft fat, since the latter should not be sliced so quickly as, say, firm meat.

A slicing machine forming one embodiment of the invention is illustrated by way of example in the accompanying drawings, in which:

Figs. 1 and 2 are elevations of the machine taken at right angles to each other;

Fig. 3 is a detail section view drawn to a larger scale, the section being on the line III-III of Fig. 2.

The slicing machine shown comprises a base 1 whereon is slidably mounted, in known manner, a carriage 2 provided with handle 3

and with a clamping device 4 for holding the substance S to be sliced on a feed plate 5 mounted on the carriage 2 and slidably transversely thereof as usual. Feed-mechanism (not shown) of well-known construction would be provided for feeding the feed-plate 5 with the substance S thereon towards a rotary knife 6 journaled in a bracket 7 upstanding from the base 1. The bracket 7 supports an electric motor 8, on the shaft of which is carried a sprocket-wheel 9 chain connected to a sprocket-wheel 10 on the knife, the chain being indicated by the dotted line 11. The carriage 2 is coupled to a crank 13 by a connecting rod 14, the crank 13 being secured to the upper end of a vertical crank-shaft 15 journaled in, and passing through, the base 1. At its lower end, the crankshaft 15 carries a bevel wheel 16 meshing with a bevel pinion 17 on a horizontal shaft 18 also journaled in the base 1 and passing to the exterior thereof.

The crank shaft 15, at a point substantially midway of its length, carries a horizontal flywheel 19 (indicated in dotted lines in Fig. 1) and it has a driving connection by the parts 18, 26, 27 with the knife shaft 20, the connection including essentially a slip-coupling 21, 22. One element 21 of the slip-coupling is formed on, or is secured to, the horizontal shaft 18, while the other element 22 is freely mounted on the shaft 18 and is urged by a spring 23 (Fig. 3) to make frictional contact with the other element 21. The external end of the shaft 18 is journaled in a bush 24 presenting an abutment for the spring 23. The bush 24 is screw-threaded into a boss 25 rigid with the base 1 and, by adjusting the bush, the pressure of the spring and, consequently, the frictional grip by the co-acting faces of the elements 21, 22, can be adjusted. The element 22 has secured to it the sprocket wheel 26 driven by the chain 27 from the sprocket wheel 28 on the knife shaft 20, which latter is driven by the chain gear 10, 11, 9 from the motor 8.

The elements 21, 22, or one of them, may be faced in known manner with friction material.

In the working of the machine, when cut-

ting a piece of substance the nature of which varies, the knife will maintain a constant rotational speed, whereas, by virtue of the slip-coupling, the speed of the carriage 2 may be varied by the operator according to the kind of substance being sliced. For this purpose, the operator may grasp the handle 3 and may either assist the motor to reciprocate the carriage or retard the speed thereof to suit the nature of the substance being sliced.

If desired, the bush 24 might be slackened back to an extent which would render the slip-coupling inoperative. Thereafter, the carriage could be reciprocated by hand, while the knife could be motor-driven or might remain at rest, this latter arrangement being desirable for the cutting of cheese. Further, for the purpose of sharpening the knife in known manner, the carriage might remain at rest while the knife could be rotated by the motor.

It is to be understood that the slicing machine illustrated has been chosen simply by way of example, and that the invention could be readily applied to other types of slicing machines. For instance, the invention might be applied to slicing machines of the type in which the knife is driven by a motor as in the construction above set forth, but in which the carriage is connected through the usual crank-and-connecting-rod mechanism with a manually turnable flywheel (as indicated by the dotted lines F in Fig. 2). The horizontal shaft of the flywheel F would be geared to the bevel wheel 16 in the usual well-known manner, while the flywheel 19 and the handle 3 would be dispensed with. In operation, the knife would maintain a constant rotational speed and, by virtue of the slip-coupling, the operator could vary the slicing speed, in accordance with the nature of the substance, by means of the flywheel F.

Moreover, the slip-coupling shown has been chosen simply for the purposes of illustration and it may be modified in construction without departing from the scope of the invention.

I claim:—

1. In a slicing machine the combination with a rotating slicing knife of a reciprocating work table, a source of power operatively connected to said knife and table to drive the same, said connection to said table including a slip-coupling comprising two members in engagement with each other but movable relative to each other when said table is retarded or accelerated by manual force supplied thereto, said members being moved relatively to each other without destroying the operative connection therebetween, and manual means on said table for applying a manual force thereto for the purpose of moving said table at a greater or lesser speed than that at which the table is normally driven from said source of power without

destroying the driving connection therebetween.

2. In a slicing machine the combination with a rotating slicing knife of a work table, mechanism for reciprocating said table, a source of power connected to said knife for operating said mechanism, said mechanism including a shaft geared to said table, fixed and movable friction members on said shaft, said movable member being connected to said source of power, said friction members being movable relative to each other whenever the speed of the friction member fixed to said shaft is varied from the speed imparted thereto by said source of power, and manually operable means on the carriage for selectively operating said friction member fixed to said shaft at a speed greater or less than the speed at which said movable friction member is driven by said source of power without destroying said driving connection between said members.

3. A slicing machine having a rotating slicing knife, a work table, a frame, a shaft journaled in said frame, a gear on said shaft, one end of said shaft being operatively connected to said table to reciprocate the same, a second shaft journaled in said frame, a second gear on said second shaft meshing with said first gear, said second shaft having a friction member secured thereto and a co-operating friction member rotatably mounted thereon, a nut adjustable on said shaft, a spring between said nut and rotatably mounted friction member, a power wheel fixed to said loosely mounted member, a source of power, a connection between said source of power and said wheel, and a connection between said knife and said source of power for driving said knife, said nut being adjustable to vary the amount of force necessary to rotate said friction members relative to each other for a given force manually applied to said table for the purpose of accelerating or retarding the normal speed given to said table by the operative connections between said table and said source of power, manually operable means on said table for selectively operating said first mentioned friction member at a greater or less speed than the speed at which the movable friction member is driven by said source of power, said friction members maintaining their driving relation to each other even when manual force is applied thereto to increase or decrease the normal reciprocation thereof.

In testimony whereof I have signed my name to this specification on this 12th day of April A. D. 1928.

JETZE VAN HOORN.
